UNITED STATES PATENT OFFICE.

ARTHUR ROSSI, OF SAN FRANCISCO, CALIFORNIA.

COMBINED GRAPE CRUSHER, STEMMER, AND MUST-PUMP.

1,094,817.

Specification of Letters Patent.

Patented Apr. 28, 1914.

Application filed July 25, 1913. Serial No. 781,277.

To all whom it may concern:

Be it known that I, ARTHUR ROSSI, a subject of the King of Italy, residing in the city and county of San Francisco, State of California, have invented new and useful Improvements in a Combined Grape Crusher, Stemmer, and Must-Pump, of which the following is a specification.

This invention relates to combined grape crushing, stem removing and must pumping machines for the use in the process of wine making from grapes, and has for its object the production of mechanism that will complete in one continuous operation the several performances required in said process.

Another object is to obviate the defect, now met with, in machines of this nature, of the frequent clogging of the suction pipe of the must pump by pomace, and in this way eliminate the necessity of frequent stopping of the machine, the removal of all the liquid contents from the must pan, and the cleaning of the suction pipe of the must pump.

To these ends and objects chiefly my invention embraces a pair of crushing rollers located at the bottom of a feed hopper, an elevator for the delivery of clusters of grapes into said hopper, a feed controller to regulate the discharge from the hopper into the crushing rollers, means for detaching the grapes from the stems, expelling the latter from the machine, and collecting the former in a must pan, and novel devices for keeping the must agitated while in the pan.

The invention embraces further a pump to remove the must from the pan, and deliver it to a higher elevation into the must tanks.

The invention further embraces a novel construction and arrangement of parts and mechanism, producing a continuously operating machine, that will not readily clog, all as hereinafter described and set forth.

The following description explains at length the nature of my said invention, and the manner in which I proceed to apply and carry out the same in the production of an improved machine for the purpose named, reference being had to the drawings that accompany and form part thereof.

Figure 1 is an end elevation of the machine. Fig. 2 is a cross section taken through $a-a$, of Fig. 3. Fig. 3 is a front elevation. Fig. 4 is a longitudinal section on line $b-b$ of Fig. 1.

For convenience of describing the principal parts of this machine they are designated by letters.

A is a cast iron base provided with wheels or rollers a . B and B_1 are standards fastened to said base and are tied together by the channels $C-C_1$.

B_2 is a standard fastened on top of the channels.

D is a crushing roller provided with journals $d-d_1$ working in the boxes d_2 and d_3 on the standards B and B_2 , and driven by the gear d_4 .

E is a crushing roller that works co-operatively with the roller D. It is provided with the journals e_1 and e_2 , working in the bearings e_3 and e_4 held yieldingly in position in the standards B and B_2 by means of the springs e_5 and e_6 . The two crushing rollers are geared together at their rear ends by the gears d_5 and e_7 .

F is a feed hopper set above the crushing rollers adapted to receive clusters of grapes to be acted on in the machine. Inside the hopper F, somewhat above the crushing rollers D and E, is located the feed controller G, which consists of the shaft g provided with a number of prongs g_1 arranged in rows radiating from the shaft outwardly. The shaft g works in the boxes g_2 and g_3 , and is connected to the roller D by means of the gears d_6 and g_4 .

H is a feed elevator for the delivery of grapes to the feed hopper. (Shown in the drawings with the lower part broken away). It is suspended from the arms H_1 and H_2 of the standards B and B_2 and is driven by a link belt h_1 , connecting the sprocket wheel d_7 set on shaft d with a similar sprocket wheel h_2 set on the elevator shaft h_3 .

The stem removing mechanism consists of the shaft j , one end of which is mounted in the box j_1 , set in the standard B, and the other in a bracket bearing j_2 , fastened to the channels $C-C_1$ at the discharge end of the machine. It carries a number of arms j_3 extending radially and arranged in a double helix. Beneath the shaft j there is a perforated casing K semicircular in cross section. It is closed at the head end by the solid part of the standard B, while the other end, being left open passes through a circular opening in the standard B_1 and terminates just a little beyond that standard. L is a cover of solid sheet metal also semicircular in shape and when in place forms to-

gether with the casing K a complete cylindrical casing. The cover L has at its head end a funnel l which, starting from the cylindrical portion, extends upward and is then made to follow the periphery of the crushing rollers D and E and terminate to fit the discharge end of the hopper F.

M is an agitator comprising a shaft m provided with a conveyer blade m_1 . The shaft rests in the bearings m_2 — m_3 on the standards B and B_1 and carries a spur gear m_4 .

N is a pan or casing within which the must is collected. The bottom of the casing is made to follow the circle of the agitator, then the two ends extend upward and terminate at the channels C—C₁. At the discharge end of the pan N there is a discharge pipe n having a flange n_1 suited to fit a similar flange n_2 of the suction pipe P₆ of the must pump P.

P₁ and P₂ are standards fastened to the base A, which carry the pump cylinders P₃ and P₄. The pump body P₅ is fastened to the base A₁. It has a suction pipe P₆ and a discharge pipe P₇.

Q and Q₁ are cranks set on the ends of the crank shaft Q₂ to operate the pistons in the cylinders P₃ and P₄.

R is a counter shaft which rests with one end in the box on the standard B and with the other in the box r₁ on the standard P₁; its object is to transmit the motion from the shaft j to the crank shaft Q₂ of the pump by means of the gears j₁, r₂, r₃, and Q₃.

The following is the operation of the machine: The shaft j is driven either by a belt and pulley or by a motor (not shown in the drawings). This rotary motion is transmitted to the crushing rollers D and E through the gears j₄, d₄, d₅ and e₅. The feed controller shaft g is driven by the roller D through the gears d₆ and g₄ while the elevator shaft h₃ is run from the same roller D by the link belt h₁ and sprocket wheels d₇ and h₂. The agitator shaft shaft m is operated from the shaft j by means of the gears j₄, r₂, and m₄ while the pump shaft derives its motion from the same shaft j through the gears

j₅, r₂, counter shaft R and gears r₃ and Q₃. All the shafts have their motions in the directions shown in the drawings by the arrows. The material to be handled by the machine, consisting of clusters of grapes, is fed by hand upon the belt of the elevator H and is discharged by the latter into the hopper F above the feed controller G. From here it is fed at a steady rate between the crushing rollers D and E by the slow and steady rotation of the controller G. The crushing rollers after rupturing the shells of the grapes and pressing out the must, discharge the material through the funnel l, letting it fall into the casing K, where the juice of the grapes drains down through the

perforated casing K into the pan N, while the stems and the shells are caught by the prongs j₃ of the stem removing mechanism running at a high rate of speed and are carried around and dragged along the walls of the casing K and cover L. The shells or skins of the grapes get detached from the stems, while moving along the rough perforated surface of the casing K and are discharged through the perforations into the pan N, while the stems are gradually carried toward the discharge end of the machine by the prongs j₃, which being spaced in a helix have, to a great extent, the effect of a screw. The juice and shells of the grapes after passing the perforated casing K collect in the pan N. The must collected in the pan N while kept agitated by the motion of the helical blade m₁ is driven toward the discharge pipe n, where it arrives in a state of uniform consistency, being fluid enough to be drawn in by suction into the pump cylinders P₃ and P₄ and discharged through the pipe P₇ into the must tanks at a considerable height above.

The crushing rollers D and E may be omitted in some machines built under this design. In such case the clusters of grapes delivered into the hopper F are directly fed by the controller G into the casing K and L through the funnel l, where they are caught by the prongs j₃ and subjected to a rapid peripheral speed.

The shells or skins of the grapes, due to impact against the stationary walls of the inclosing casing, become ruptured, detached from the stems and discharged through the perforated casing K into the must pan N.

It is evident that by the arrangement of the mechanism as illustrated in the drawings and described above, the performance of the machine is continuous and the tendency of clogging of the suction pipe of the must pump is entirely eliminated by keeping the pomace of uniform consistency before it becomes subject to the action of the pump in the suction pipe.

What I claim and desire to secure by Letters Patent is:

1. In a machine of the character described the combination of a pair of crushing rollers, a feed hopper, a feed controller placed between said crushing rollers and said hopper, means for the separation and discharge of the stems, a must pump for the removal and delivery of both solids and liquids of the pomace and means to drive said crushing rollers, feed controller and must pump.

2. In a machine of the character described the combination of a pair of crushing rollers, a feed hopper, a feed controller placed between said crushing rollers and said hopper, an elevator for the delivery of material into said hopper, means for the separation and expulsion of stems and a must pump for the

removal and delivery of both solids and liquids of the pomace.

3. In a machine of the character described the combination of a pair of crushing rollers 5 adapted to receive clusters of grapes to be crushed, means for effecting the separation and expulsion of the stems, a pan for the collection of the must, a must pump for the removal and delivery of both solids and liquids of the pomace, a discharge pipe leading from said pan to the suction pipe of said must pump and means operating to agitate the must in said pan.

4. In a machine of the character described 15 the combination of a pair of crushing rollers adapted to receive clusters of grapes to be crushed, a feed hopper, a feed controller placed between said hopper and said crushing rollers, means acting to separate and 20 expel the stems, a pan for the collection of the must, a must pump for the removal and delivery of both solids and liquids of the pomace and means operating to agitate the must in said pan.

25 5. In a machine of the character described the combination of a pair of crushing rollers adapted to receive clusters of grapes to be crushed, means acting to separate and expel the stems, a pan for the collection of the must, 30 a must pump for the removal and delivery of both solids and liquids of the pomace and an agitator comprising a shaft provided with a helical blade, means to drive said crushing rollers and means to drive said agitator 35 shaft.

6. In a machine of the character described the combination of means adapted to receive and crush bunches of grapes, means for the separation and expulsion of the 40 stems, a must pan, a must pump for the removal and delivery of both solids and liquids of the pomace and means acting to keep the material agitated while in the must pan.

45 7. In a machine of the character described the combination of means adapted to receive and crush clusters of grapes, a feed hopper, a feed controller placed between said means

and said hopper, mechanism for the separation and expulsion of the stems, a must pan 50 and a must pump for the removal and delivery of both solids and liquids of the pomace.

8. In a machine of the character described the combination of a feed hopper adapted 55 to receive clusters of grapes, means for the separation and discharge of the stems, a controller governing the discharge from said hopper into said means, a pan for the collection of the must, a must pump for the removal and delivery of both solids and liquids 60 of the pomace, and means acting to keep the material agitated while in the must pan.

9. In a machine of the character described the combination of means adapted to receive 65 clusters of grapes, a feed controller, means for the separation and expulsion of the stems, a must pan and a must pump for the removal and delivery of both solids and liquids of the pomace.

70 10. In a machine of the character described the combination of means adapted to receive clusters of grapes, means for the separation and expulsion of the stems, a must pan, a must pump for the removal and delivery 75 of both solids and liquids of the pomace and means acting to keep the material agitated while in the must pan.

11. In a machine of the character described a feed hopper adapted to receive 80 clusters of grapes, a feed controller, means adapted to separate and discharge the stems, a must pan, a must pump for the removal and delivery of both solids and liquids of the pomace, supporting standards for said 85 hopper, feed controller and must pan and standards for said must pump, and a base resting on wheels or rollers.

In testimony whereof I have signed my name in the presence of two subscribing 90 witnesses.

ARTHUR ROSSI.
